Attorney

UNITED STATES PATENT OFFICE.

ELLIE ALEXANDER LEVY, OF FORT WORTH, TEXAS.

DESIGN FOR A BADGE.

49,390.

Specification for Design.

Patented July 18, 1916.

Application filed May 9, 1916. Serial No. 96,454. Term of patent 14 years.

To all whom it may concern:

Be it known that I, ELLIE ALEXANDER LEVY, a citizen of the United States of America, residing at Fort Worth, in the county of Tarrant and State of Texas, have invented a new, original, and ornamental Design for Badges, of which the following is a specification, reference being had to the accompanying drawing, forming part thereof.

The figure is a face view of the badge, showing my design.

I claim:

The ornamental design for a badge, substantially as shown.

Signed at Fort Worth, in the county of Tarrant, and State of Texas, February 21, 1916.

ELLIE ALEXANDER LEVY.
